UNITED STATES PATENT OFFICE.

EDWARD E. KLEINSCHMIDT, OF NEW YORK, N. Y., ASSIGNOR TO KLEINSCHMIDT ELECTRIC COMPANY, INC., OF NEW YORK, N. Y., A CORPORATION OF NEW YORK.

KEYBOARD TAPE-PERFORATOR.

1,085,984.

Specification of Letters Patent. Patented Feb. 3, 1914.

Application filed March 15, 1910. Serial No. 549,492.

To all whom it may concern:

Be it known that I, EDWARD E. KLEINSCHMIDT, a citizen of the United States of America, residing at the city of New York, 5 State of New York, have invented certain new and useful Improvements in Keyboard Tape-Perforators, of which the following is a specification.

The perforating machine forming the subject-matter of this invention is designed to 10 make perforations or punctures in a strip of paper in selected groups, of various arrangements and number of punctures, adapted to act as a medium for controlling 15 intermittent electric currents, and particularly adapted for use in telegraphic transmission. The organization is such that one or more rows of punctures may be made through the strip of paper; each group of 20 which will represent a letter or signal, all the punctures of each group being simultaneously produced upon the depression of a finger piece in a keyboard or bank of keys, arranged in a manner similar to that of an 25 ordinary type-writing machine.

The invention involves the use of as many punches as there are punctures required to produce the greatest number of signaling impulses in any one of the groups; 30 controllers for the punches for putting them individually in condition ready for action; selectors actuated by the levers or finger pieces of the keyboard which set the controllers of the punches required to produce 35 the electrical signal equivalents of the characters and signs on the finger pieces of the keyboard; means for operating the punches of the selected controlling devices that have been set by the selectors of the key levers, 40 which means is preferably of an electrical character energized by the closing of an electric circuit by each and all of the key levers just after their selectors have set the controllers; means for feeding the strip of 45 paper after a group of punctures has been made, one of its features being to feed variable lengths of paper corresponding to the distances on the paper occupied by the groups of punctures which will be of different 50 lengths; a locking device, also preferably electrically actuated, for holding the strip of paper stationary when the feeding device is receding to take a new grip on the paper.

The invention also includes a simple 55 means for actuating the punch controllers from the selectors of the key levers consisting of a series of flexible strands or wires for the controllers of each row of punches used, stretched between a fixed 60 frame and the controllers and laterally bent or flexed by the selectors, thereby drawing the controllers in a direction toward the fixed ends of the wires.

In the accompanying drawings, Figure 1 65 is a front elevation of the machine; Fig. 2, a plan view of the same; Fig. 3, a left-hand side elevation; Fig. 4, a transverse section through the key levers, showing the flexing wires upon which they act and the punch 70 controllers connected to the wires; Fig. 5, a sectional view of the keyboard manipulating part of the machine, lengthwise of the key levers; Fig. 6, a cross section of Fig. 5, taken on the line 6, 6; Figs. 7, 8 and 9 are 75 similar view of the perforating mechanism, taken on the line 7, 7 of Fig. 1, showing the frame in section and the operating devices in different positions; Fig. 10, a front elevation of the perforating mechanism, taken 80 on the line 10, 10 of Fig. 7, showing some of the parts in section; Fig. 11, a sectional view of the same, looking in the same direction as in Fig. 10, taken on the line 11, 11 of Fig. 7; Fig. 12, a sectional view of the 85 perforating part of the press, showing the punches and their controlling devices; Fig. 13, a plan view of the same taken on the line 13, 13 of Fig. 12; Fig. 14, a side elevation of the paper feeding device; and Fig. 90 15 is a detached front view of the paper and paper feed locking device. Figs. 7 to 15 inclusive, are drawn to a larger scale than the preceding views.

The general character of the manipulating 95 part of the machine is that of ordinary type-writing machines, the keys of the key-board *a* being provided with the usual letter characters when the code signs for electrical transmission correspond thereto. Transversely arranged beneath the key levers *b* are two superimposed rows of flexing wires *c* and *d* normally held under tension, each being secured at one end to a bracket piece *e* and at the other end to one end of a punch controller *f* or *g*, to the other ends of which are attached tension springs *h*. The upper set *c* of the wires connect to and operate the up- 100 105

per set *f* and the lower set *d* connect to and operate the lower set *g* of the punch controllers. Each of the punch controllers when set in operative position causes the punch *i* controlled by it to puncture the strip of paper *j*, as hereinafter described; two rows of perforations being formed by the two sets of punches controlled by the two sets of controllers *f* and *g*, suitable for telegraphic transmission according to the "Delany system" as practised by the Telepost Company; and the arrangement of the perforations may accord with the letter signals of the "Morse" or "Continental" code. The selection of the corresponding punches is attained by the selectors *k* and *l*, which are variably notched ledges on the undersides of the key levers *b* arranged to bear on and flex the wires *c* and *d* respectively, as the key levers are manipulated, to draw the punch controllers *f* and *g* at the movable ends of the wires toward the fixed ends of the wires. To insure a proper substantially uniform contact between the selector ledges *k* and *l* and the two rows of wires *c* and *d*, when in normal quiescent state, the central ledges are deeper or lower down than the end ones, the lines including the edges of the two sets of ledges being curvilinear or lower at the central part, as shown at Fig. 4. The wires are controlled as to vertical movement at the two sides of the bank of key levers *b* by a guide plate *m* near the fixed ends of the wires, through holes in which the wires pass, and by grooved rollers *n*, located between the key levers and the punch controllers *f*, *g*, and over which the wires extend and by bars *o* arranged above the rollers *n*. These wire guides, the plate *m* and rollers *n*, are angularly arranged relatively to the wires, as shown at Figs. 1 and 2, thus causing variations in the lengths of the parts of the wires that are flexed by the selector ledges *k* and *l*, and so afford compensation for the variable angular displacements due to the different positions in which the ledges *k* and *l* act on the wires lengthwise between the guides *m* and *n*. To assist this compensation and insure as perfect uniformity as possible of action of the key-levers on the punch controllers the positions of the finger pieces of the keys in the different rows of the key-board should also be compensated so each key lever *b* is provided with an independent pivotal connection *p*, whose distance from the flexible wires is correlated to the distance the finger piece is from the wires, to give about the same ratios between said distances.

The perforating mechanism and paper feed device are actuated through the medium of electromagnets, whose circuits are closed by a forked arm *q* pivoted at *r* to a lug or bracket on the main frame and caused to contact with the terminal plates *s* and *t*,

having insulated connections with the frame through the rod *u* which forms the ends of two levers *v*, pivoted at *w* and connected at their other ends by a bar *x* lying beneath the key-levers and acted upon by a ledge *y* 70 on each of the key-levers as each key-lever is depressed. The parts are so arranged that contact is made between *q*, *s* and *t* just after the punch controllers are set by the flexing of the wires *c* and *d*, see Figs. 5 and 6. Springs *z*, connected to a frame 1 and to the levers *v*, hold the bar *x* in operative position beneath the key-levers and contact arm *q*, normally away from the plates *s* and *t*. This frame 1 also carries springs 2, that are connected to and hold the key-levers up against a stop bar 3. A spacing bar 4 has its side arms 5 pivoted at 6 to the frame at its rear end. The arms 5 extend over the bar *x*, and act to depress it to close the electric circuit when the spacing bar is manipulated. 80

The strip or ribbon of paper *j* to be perforated is wound on the reel 7, from whence it passes over the core or armature 8 of the electro-magnet, shown in Figs. 7, 8 and 9 as a solenoid 9, that actuates the paper perforating and feeding devices. The paper then passes over the die 10 of the punching press to the feeding disk 11, and to the winding up reel 12, driven by a friction slip pulley 13, of ordinary construction, which receives motion by a belt or cord 14 from the pulley 15, on the same axis as and driven by the feed disk 11. 90

The armature 8 is provided with a cross-head 16, connected by links 17 to the free ends of levers 18 and 19 fitted to rock on an axis 20, having bearings in the frames 21 and located over the platen of the punching press. One of the levers 18, extends beyond the axis 20 and continues in a downward direction as a triangular frame 22. The other lever 19 does not extend beyond the axis 20. The magnet coil 9 is secured at its lower end to a yoke bracket 23 fastened to the under side of the main frame and above the main frame over the magnet is another upwardly extending frame having a cross-bar 24, centrally provided with an adjustable stop 25 to limit the upward movement of the armature 8 and to act with the armature to grip and hold the strip of paper *j*, to prevent undue slackness in the strip when moved forward by the feeding device. Springs 26 arranged between the upper ends of the arms 27 of the frame that has the cross-bar 24, and the ends of the cross-head 16, raise the core 8, and act to reset in normal position all the devices actuated by the core, (Fig. 7). 105

The bracket piece 28, secured to the main frame, constitutes the body of the punching press, it being provided with guide holes in the extensions 29 and 30 for the reception 110

of the punches *i* that slide freely in said holes in these extensions and are arranged in two rows. Each punch *i* has a collar between which and the lower extension is placed a coil spring 31, that holds the lower end of the punch above a groove, for the passage of the paper, with the collar bearing against the upper extension 29. Below the extension 30 is secured the die plate 32, so that said extension acts as a stripper for the punches as they are raised by their springs 31 after being caused to puncture the paper, see Fig. 11. The platen 33 of the press is formed with two sets of grooves in which the two sets of controllers *f* and *g* slide. The punches *i* extend upwardly through holes in the platen with the upper ends of one set in line with the lower faces of the lower set of controllers *g*; and the upper ends of the other set of punches in line with the lower faces of the upper set of controllers *f*. The last mentioned set of punches extend upwardly beyond the body portions of the lower set of controllers *g*. Each controller has a lateral projecting lug that is normally out of the path of the punch controlled by it, those on the upper set *f* being marked 34 and those on the lower set *g* being marked 35. The controllers are held in these positions by the springs *h* and moved forward against the resilience of the springs by the flexing wires *c* and *d*, as before described, see Figs. 11, 12 and 13, from which it is evident that, with the parts as there shown, movement will be imparted only to the punches (should the platen be reciprocated) whose controllers are pulled forward and whose lugs 34 and 35 are over their respective punches. Extending from the top of the platen are lugs 36 to which the levers 18 and 19 are pivoted, and lugs 37 to which is pivoted the short arm of the bell crank lever 38 whose fulcrum 39 is on a stud projecting inwardly from the side frame 21, and whose long arm is connected by link 40 to the arm 41 securely fastened to the levers 18 and 19 at their point of rocking on the axis 20. From this arrangement it will be seen that the platen 33 will be held in a horizontal position as it is moved by the depression of the ends of the levers 18 and 19 connected to the armature 8 of the magnet 9. A floating lever 42 has as its moving fulcrum a connection 43 to the end of a swinging arm 44 pivotally connected to the lower end of a bracket 45 depending from the lower side of the main frame, beneath and at one side of the punching press. This moving fulcrum 43 is surrounded by an irregular shaped opening 46 formed through the lower end of the triangular extension 22 of the lever 18. The upper end of the long arm of the lever 42 moves in a path alongside the platen 33, clear of the downwardly extending lugs 47 that form parts of the

punch controllers *g* when said controllers are in inactive positions, as shown in Figs. 7 and 11. In Fig. 7 the end of this lever is shown resting against a stop pin 48, and a bent plate 49 attached to the lever near its end forms, with the face of the lever, a fork that embraces one of the lugs 47 when this end of the lever is moved. The lower end 50 of the short arm of the lever 42 is, by an adjustable link 51, connected to the short arm 52 of the feed lever 53 which is fitted to rock on the axle of the feed disk 11 at both sides thereof, the upper end of this lever 53 being provided with a gripping jaw 54, of ordinary make, adapted to grip the strip of paper *j* on the disk 11 and carry the paper and disk with it as it moves forwardly into the position shown at Fig. 7. To prevent any disturbance of the paper and feed disk 11 when the feed lever is moved back by the action of magnet 8, 9, to take a fresh grip of the paper, as shown at Fig. 9, a locking device is provided consisting of gripping jaw 55, pivoted at 56 to an arm adjustably connected to the main frame. An adjustable link 57 connects the pivoted jaw 55 to the end of the armature 58 of an electro-magnet 59, which, being energized at the same time as the solenoid 9, locks the disk 11 and paper when the feed lever is moving back, but releases them, because of the current being cut off from magnet 59, when the feed lever is moving the paper forward. A small torsional spring 60, Fig. 15, presses the jaw 54 against the paper, when it is to lock the same, and the spring 61 connected between link 57 and the main frame of the machine, carries the jaw away from the paper when the armature 58 becomes demagnetized.

The pulley 15 that imparts motion to the winding up reel 12, through its friction drive pulley 13, has a yielding connection with the feed disk 11, consisting of a coil spring 62, one end of which is fastened to the pulley 15 and the other end to a stud 63 projecting from the side of the disk 11, the arrangement being such that as the disk is rotated in feeding the paper the tendency is to further wind up the spring 62. The pull of the outer end of the spring on pulley 15 is in a direction to wind the paper on the reel 12, and to keep the paper taut between this reel and the feeding device. The spring 62 has two functions; it cushions the strain on the paper as the feeding device, which is somewhat sudden in its action, commences to act, and insures a uniform tautness to the paper as it is wound on the reel 15 and when the feed is at rest.

Referring to Figs. 7, 8 and 9, it will be seen that during the first part of the movement of the armature 8, its magnet being energized as, or immediately after, a group of punch controllers has been set by the ma-

nipulation of a key lever as before described, the platen 33 is carried down sufficiently to bring the lugs 47 of the set punch controllers *g* into the path of movement of 5 the lever 42, by which time the extension 22 of the lever 18 has brought the opening 46 into such position that its rear wall has contacted with the pivot 48 of lever 42 and moved the lever forward, with its lower pivotal 10 connection 50 as its fulcrum, until it is arrested by its upper end striking the first one of the lugs 47 of the set group it meets in such movement, which may be any one of the lugs according to code signal or other 15 groups of punctures required in the strip of paper. Fig. 8, also shows that during this part of the operation the feed lever 53 with its gripper has remained stationary in its forward position. Now the upper end of 20 the lever 42 becomes its fulcrum by bearing against the set acting lug 47 and a continuation of the downward movement of armature 8 causes the rear wall of the opening 46 of lever 18 to further act on the pivotal 25 connection 43 and carry the lower end of lever 42 forward, and the link 51 pushes the feeding device 53, 54 back over the paper on the feed disk 11 into a feeding position. The bent plate 49 at the end of the 30 lever 42 is then in front of the said lug and the upper end of the lever is held in proper working position until a backward movement is given to the lever, as shown at Fig. 9, the pivotal connection 43 being stopped 35 by the swinging arm 44 resting against the stop screw 64 extending through an arm of the bracket 45. When the current is cut off from the magnet 9, on release of the key lever that caused it to be energized, the 40 springs 26 reset the parts into normal inoperative positions, but during the first part of the retrograde movement the platen 33 rises and the punches *i* are raised within the stripper clear of the die 32 and of the paper 45 *j*. This occurs before the front wall of opening 46 contacts with the pivotal connection 43 to move lever 42 and link 51 back into the positions shown at Fig. 7, thereby causing the feed lever 53 to move forward 50 and, by its gripper 54, carry the paper and feed disk 11 with it. At such times the locking device 55 is inactive as the current is cut off from its operating magnet 59 at the same time the magnet 8, 9, becomes inactive. The arrangement of the parts here described affords a simple and accurate means for varying the lengths of paper fed to accord with the lengths of code signals to be transmitted. It will readily be 60 seen that the farther from the front of the machine the upper end of the lever 42 is arrested, the greater will be the distance that the feeding device 53, 54 is moved back over the feed disk 11, and the longer the 65 section of paper fed, the said device having

a fixed position of rest when in normal inoperative position. All the parts then again assume the positions shown at Fig. 7.

A projection 147 on the platen 33 serves to effect space feed of the paper when the space key or bar is depressed, the operation being the same as when the paper feed is made effective by the several lugs 47.

I claim:

1. In a perforating machine, a reciprocating punch head, a plurality of punches, a support independent of the punch head in which said punches are mounted to slide, punch controllers mounted to reciprocate in the punch head, a keyboard selector mechanism comprising key levers with direct connections to the controllers and adapted to set the controllers in groups corresponding to the characters on the keyboard, and means for moving the punch head to cause the set controllers to engage and operate the corresponding punches. 75

2. A perforating machine comprising a punching press having a reciprocating platen, two rows of punches normally inactive when the press containing them is operated, punch controllers adapted when set to put the punches in operative condition, selectors for setting the controllers in various groups, means for actuating the platen 90 of the press and thereby operating the punches that are made operative by the set controllers, a feeding device set in operative position by the platen actuating means and adapted to feed a strip or ribbon under the punches after the punches have acted thereon, means for adjusting the feeding device to vary the length of paper fed, controlled by one of the punch controllers, and means for operating the feeding devices. 95

3. A perforating machine comprising a number of punches normally inactive when the press containing them is operated, punch controllers adapted when set to put the punches in operative condition, wires secured 110 at one of their ends to a stationary part of the machine and at their other ends to the controllers, selectors adapted to flex different selections of the wires for setting the controllers in various groups, and means for actuating the punches that are made operative by the set controllers. 115

4. A perforating machine comprising a number of punches arranged in two parallel rows, normally inactive when the press containing them is operated, punch controllers adapted when set to put the punches in operative position, a series of stretched wires attached to the controllers of each row of punches, selectors adapted to flex certain 120 selected wires of the two series, and means for actuating the punches made operative by the set controllers. 125

5. A perforating machine comprising a number of punches arranged in two parallel 130

rows, normally inactive when the press containing them is operated, punch controllers adapted when set to put the punches in operative position, a series of stretched wires attached to the controllers of each row of punches, selectors adapted to flex certain selected wires of the two series, a feeding device for moving a strip or ribbon under the punches, means for operating the feeding device and means for actuating the punches made operative by the set controllers.

6. A perforating machine comprising a number of punches arranged in two parallel rows, normally inactive when the press containing them is operated, punch controllers adapted when set to put the punches in operative position, a series of stretched wires attached to the controllers of each row of punches, selectors adapted to flex certain selected wires of the two series, a feeding device for moving a strip or ribbon under the punches, an adjuster controlled by one of the punch controllers of one of the rows of punches for adjusting the feed to vary the length of strip moved according to the location of the punch in the row of punches that is made active by the controller, means for operating the feeding device, and means for actuating the punches made operative by the set controllers.

7. A perforating machine comprising a number of punches normally inactive when the press containing them is operated, punch controllers adapted when set to put the punches in operative condition, wires secured at one of their ends to a stationary part of the machine and at their other ends to the controllers, selectors adapted to flex different selections of the wires for setting the controllers in various groups, means for actuating the punches that are made operative by the set controllers, comprising an electro-magnet and its movable armature, a circuit closer therefor, and means for actuating the selectors and the circuit closer.

8. A perforating machine comprising a number of punches normally inactive when the press containing them is operated, punch controllers adapted when set to put the punches in operative condition, selectors for setting the controllers in various groups, a feeding device for moving a strip or ribbon under the punches, means for actuating the operative punches and feeding device, a locking device for holding the strip or ribbon during the backward movement of the feeding device, and means for operating the locking device.

9. A perforating machine comprising a number of punches normally inactive when the press containing them is operated, punch controllers adapted when set to put the punches in operative condition, selectors for setting the controllers in various groups, a feeding device for moving a strip or ribbon

under the punches and means for actuating the operative punches and feeding device the latter being provided with a gripping device for clamping the strip or ribbon before it passes under the punches.

10. A perforating machine comprising a number of punches normally inactive when the press containing them is operated, punch controllers adapted when set to put the punches in operative condition, selectors for setting the controllers in various groups, a feeding device for moving a strip or ribbon under the punches, means for actuating the operative punches and feeding device, a locking device for holding the strip or ribbon during the backward movement of the feeding device, means for operating the locking device, and means for actuating the selectors and for setting in action the means for operating the punches and the locking device.

11. A perforating machine comprising a punching press having a reciprocating platen, two rows of punches normally inactive when the press containing them is operated, punch controllers adapted when set to put the punches in operative condition, selectors for setting the controllers in various groups, a key-board each key lever of which actuates a selector, means for operating the punching press comprising an electro-magnet and its movable armature, a circuit closer therefor adapted to be closed when a key lever is depressed and a feeding device for moving a strip or ribbon under the punches and an adjustable connection between the punch operating means and the feeding device.

12. A perforating machine comprising a number of punches normally inactive when the press containing them is operated, punch controllers adapted when set to put the punches in operative condition, selectors for setting the controllers in various groups, a feeding device for moving a strip or ribbon under the punches, means for actuating the operative punches and feeding device, a locking device for holding the strip or ribbon during the backward movement of the feeding device, means for operating the locking device, the said means for actuating the punches and the feeding device and the means for locking the strip or ribbon being provided with electro-magnets, and a circuit closer actuated to cause the magnets to be energized just after the controllers have been set by a selector.

13. In a perforating machine, a series of punches fitted to independently slide in guides of a press, a platen adapted to move in direction toward and from the die and into which the upper ends of the punches extend, a controller for each punch carried by the platen, which when set in one position causes the punches to be moved with the

platen and when set in another position the platen may be moved without imparting motion to the punches.

14. In a perforating machine, a punching press having a plurality of punches, a feeding mechanism adapted to move a strip or ribbon through the punching press, and comprising a floating lever connected at one end to the feeding device and supported by a movable joint, the other end acting on a stop on the platen of the press, and a motor or power transmitter connected to the platen of the press and to the movable joint of the floating lever.

15. In a perforating press, a feeding device adapted to intermittently feed a strip or ribbon through the press, a floating lever having three connecting joints, means for reciprocating the platen of the press and for changing the position of one of the joints of the floating lever causing it to rock on another of the joints which is connected to the feeding device, thereby bringing the free end, as a third joint, into connection with a stop on the platen, which then, upon the further forward movement and part backward movement of the first joint, acts as the fulcrum of the lever and causes the feed connected joint to move and actuate the feeding device.

16. In a perforating press, a feeding device adapted to intermittently feed a strip or ribbon through the press, a platen provided with a series of movable stops, a floating lever having three connecting joints, means for reciprocating the platen of the press and for changing the position of one of the joints of the floating lever causing it to rock on another of the joints which is connected to the feeding device, thereby bringing the free end, as a third joint, into connection with a set stop on the platen, which then, upon the further forward movement and part backward movement of the first joint, acts as the fulcrum of the lever and causes the feed connected joint to move and actuate the feeding device.

17. In a perforating press, a feeding device adapted to intermittently feed a strip or ribbon through the press, a platen provided with a series of movable stops, a floating lever having three connecting joints, means for reciprocating the platen of the press and for changing the position of one of the joints of the floating lever causing it to rock on another of the joints which is connected to the feeding device, thereby bringing the free end, as a third joint, into connection with a set stop on the platen, which then, upon the further forward movement and part backward movement of the first joint, acts as the fulcrum of the lever and causes the feed connected joint to move and actuate the feeding device and a locking device for holding the strip or ribbon against

the backward movement of the feeding device.

18. In a perforating machine, a series of punches, each provided with a spring and fitted to independently slide in guides of a press and normally held by their springs above the die, a platen adapted to move in direction toward and from the die and into which the upper ends of the punches extend, a controller for each punch carried by the platen, which when set in one position causes the punches to be moved with the platen and when set in another position the platen may be moved without imparting motion to the punches.

19. In a perforating press, a feeding device adapted to intermittently feed a strip or ribbon through the press, a floating lever having three connecting joints, means for reciprocating the platen of the press and for changing the position of one of the joints of the floating lever causing it to rock on another of the joints which is connected to the feeding device, thereby bringing the free end, as a third joint, into connection with a stop on the platen, which then, upon the further forward movement and part backward movement of the first joint, acts as the fulcrum of the lever and causes the feed connected joint to move and actuate the feeding device, a plurality of punches fitted to independently slide in guides above the die of the press, a controller for each punch carried by the platen and adapted to be selectively set to put the punches in various groups in operative condition, one of said controllers acting as the stop and fulcrum for the free end of the floating lever.

20. In a perforating press, a feeding device adapted to intermittently feed a strip or ribbon through the press, a floating lever having three connecting joints in a straight line or substantially so, a rocking arm connected to the central joint of the lever, a connection between one of the end joints and the feeding device, a stop on the platen of the press with which the other end of the lever makes a pivotal connection, a stop against which this end of the lever rests in its backward position and means for operating the platen and for controlling the position of the central joint of the lever and the rocking arm.

21. In a perforating press, a feeding device adapted to intermittently feed a strip or ribbon through the press, a floating lever having three connecting joints in a straight line or substantially so, a rocking arm connected to the central joint of the lever, a connection between one of the end joints and the feeding device, a stop on the platen of the press with which the other end of the lever makes a pivotal connection, a stop against which this end of the lever rests in its backward position, means for operating

the platen, and a slip-joint connection from said means to the central joint of the lever.

22. In a perforating press, a feeding device adapted to intermittently feed a strip or ribbon through the press, a floating lever having three connecting joints, means for reciprocating the platen of the press and for changing the position of one of the joints of the floating lever by a slip-joint connection, causing it to rock on another of the joints which is connected to the feeding device, thereby bringing the free end, as a third joint, into connection with a stop on the platen, which then, upon the further forward movement and part backward movement of the first joint, acts as the fulcrum of the lever and causes the feed connected joint to move and actuate the feeding device.

23. In a perforating machine, a feeding device for moving a strip or ribbon through the puncturing press, a platen, a motor device connected to the platen and to the feeding device, a clamping means controlled by the motor device to hold the strip or ribbon as it approaches the puncturing device and just after the feeding device has acted.

24. In a perforating machine, a feeding device for moving a strip or ribbon through the puncturing press, a motor device connected to the platen and to the feeding device, a clamping means controlled by the motor device to hold the strip or ribbon as it approaches the puncturing device and just after the feeding device has acted, and a gripper for holding the fed portion of the strip or ribbon in front of and during the retrograde movement of the feeding device.

25. In a perforating machine, a feeding device for moving a strip or ribbon through the puncturing press, a motor device connected to the platen and to the feeding device, said connection comprising a lever frame having its fulcrum on the frame of the puncturing device, a connection to the top of the platen, a bell crank lever also connected by one of its arms to the top of the platen, and a link connecting the other arm of the bell crank lever to an arm of the lever frame, and a clamping means controlled by the motor device to hold the strip or ribbon as it approaches the puncturing device and just after the feeding device has acted.

26. In a perforating machine, a feeding device for moving a strip or ribbon through the puncturing press, a motor device connected to the platen and to the feeding device, said connection comprising a lever frame having its fulcrum on the frame of the puncturing device, a connection to the top of the platen, a bell crank lever also connected by one of its arms to the top of the platen, and a link connecting the other arm of the bell crank lever to an arm of the lever frame, a clamping means controlled by

the motor device to hold the strip or ribbon as it approaches the puncturing device and just after the feeding device has acted, and a gripper for holding the fed portion of the strip or ribbon in front of and during the retrograde movement of the feeding device.

27. In a perforating machine, a feeding device for moving a strip or ribbon through the puncturing press, an electro-magnet, connections between the armature or moving core of the magnet and the platen of the puncturing press and the feeding device, and a stop between which and the armature or moving core the strip or ribbon passes before it reaches the puncturing device and is gripped by and held between them when the machine is in normal quiescent state.

28. In a perforating machine, a feeding device for moving a strip or ribbon through the puncturing press, a motor device connected to the platen and to the feeding device, a clamping means controlled by the motor device to hold the strip or ribbon as it approaches the puncturing device and just after the feeding device has acted, a gripper for holding the fed portion of the strip or ribbon in front of and during the retrograde movement of the feeding device, an electro-magnet and a connection between its armature and the gripper, and means for energizing the electro-magnet and the motor device simultaneously.

29. In a perforating machine, a feeding device for moving a strip or ribbon through the puncturing press, an electro-magnet, connections between the armature or moving core of the magnet and the platen of the puncturing press and the feeding device, a stop between which and the armature or moving core the strip or ribbon passes before it reaches the puncturing device and is gripped by and held between them when the machine is in normal quiescent state, a gripper for holding the fed portion of the strip or ribbon in front of and during the retrograde movement of the feeding device, an electro-magnet and a connection between its armature and the gripper, and means for energizing the electro-magnet and the motor device simultaneously.

30. A perforating machine, including a strip or ribbon feeding device, comprising a rotatable disk and a gripping jaw adapted to hold the strip or ribbon on the periphery of the disk and move it with the disk, means for actuating the gripping jaw, a winding up reel, a pulley on the axle of the disk, a yielding connection between them, and a connection between this pulley and a pulley on the winding up reel.

31. A perforating machine, including a strip or ribbon feeding device, comprising a rotatable disk and a gripping jaw adapted to hold the strip or ribbon on the periphery

of the disk and move it with the disk, means for actuating the gripping jaw, a winding up reel, a coil spring connected at one end to the disk and at the other end to a wheel 5 or pulley fitted to rotate on the axis of the disk, and a connection between the wheel or pulley and the winding up reel.

32. In a perforating machine, a feeding device for moving a strip or ribbon through 10 the puncturing press, an electro-solenoid magnet, connections between the armature or moving core of the magnet and the platen of the punching press and feeding device, a stop between which and the armature or 15 moving core the ribbon passes before it reaches the puncturing device and is gripped by and held between them when the machine is in normal quiescent state and springs arranged to act on the core to raise it toward 20 the stop.

33. A perforating machine comprising a plurality of punches, a fixed guide in which said punches are adapted to be independently moved, a die, a reciprocating punch 25 head, a controller for each punch carried by said punch head and adapted to be moved to position back of the punches, a key board selector mechanism adapted to directly set the controllers in groups corresponding to 30 the characters on the key board, and means for moving the punch head to thereby bring the set controllers into engagement with the corresponding punches to effect the operation of the latter.

35. 34. In a perforating machine in combination, a plurality of punches to perforate a tape, punch controllers, a keyboard selector mechanism having keys one for each character to be perforated and adapted to set the 40 controllers in groups corresponding to the character on the keyboard, means for operating the punches, a feeding mechanism for the tape, and means connected to and operated by the punch operating mechanism for 45 setting the feeding device on the forward movement of the punches and for actuating the feeding device on the return movement of the punches after they have been withdrawn from the tape.

50. 35. In a perforating machine in combination, a plurality of punches to perforate a tape, punch controllers, a keyboard selector mechanism having keys one for each character to be perforated and adapted to set the 55 controllers in groups corresponding to the character on the keyboard, mechanism for operating the punches, said mechanism comprising an electromagnet, a circuit in which the said magnet is included said circuit 60 being closed when any key lever is operated, a main operating lever connected to the armature of said magnet, a feeding mechanism for the tape, and means connected to said lever for actuating the feeding mecha- 65 nism.

36. In a perforating machine in combination, a plurality of punches, controllers therefor, means for setting said controllers, and a feeding mechanism adapted to move a tape through the machine, said feeding 70 mechanism comprising a floating lever connected at one end to the feeding device, the other end acting on one of the set controllers as a stop to determine the extent of feed of the tape, and means for operating 75 said lever.

37. In a perforating machine in combination, a plurality of punches, controllers therefor, means for setting said controllers in groups corresponding to the code to be 80 perforated, and a feeding mechanism adapted to move a tape through the machine, said feeding mechanism comprising a floating lever connected at one end to the feeding device, the other end acting on the last of the 85 group of set controllers as a stop to determine the extent of feed of the tape, and means for operating said lever.

38. In a perforating machine in combination, a plurality of punches, the controllers therefor, a key board selector mechanism adapted to set the controllers in groups corresponding to the characters on the key board, a reciprocating punch head for moving said controllers, means for moving the 95 punch head comprising a main operating lever, and a feed mechanism adapted to move a tape through the machine comprising a floating lever connected to and operated by said main lever, one end of said 100 floating lever being connected to the feeding device, the other end acting on one of the set controllers as a stop to determine the extent of feed of the tape.

39. In a perforating machine in combination, a plurality of punches to perforate a tape, punch controllers, a keyboard selector mechanism having keys one for each character to be perforated and adapted to set the controllers in groups corresponding to the 110 character on the keyboard, means for operating the punches, a feeding mechanism for the tape, means connected to and operated by the punch operating mechanism for setting the feeding device on the forward movement of the punches and for actuating the feeding device on the return movement of the punches after they have been withdrawn from the tape, and means to vary the amount of feed according to the length 120 of the groups of perforations.

40. In a perforating machine in combination, a plurality of punches and means for operating the same to perforate a tape comprising a main operating lever, a feeding 125 mechanism for the tape and means connected to and operated by said main lever for setting the feeding device for operation on its forward movement, means for actuating the feeding device on the return movement. 130

of the punches after they have been withdrawn from the tape, and means to vary the amount of feed according to the length of the groups of perforations.

- 5 41. In a perforating machine in combination, a plurality of punches and means for operating the same to perforate the tape, a feeding mechanism for the tape, means for setting and for actuating the feeding device 10 comprising a floating lever, and means for locking said floating lever after it has been moved to set the feeding device for operation.
- 15 42. In a perforating machine in combination, a plurality of punches and means for operating the same to perforate a tape com-

prising a main lever, a feeding mechanism for the tape comprising a floating lever connected to and operated by said main lever, one end of said floating lever being connected to the feeding device and the other end acting on a stop to determine the extent of feed of the tape, and a fixed stop for the same end of said lever upon the return movement of the main lever. 20 25

In testimony whereof, I have hereunto subscribed my name.

EDWARD E. KLEINSCHMIDT.
